PEDESTAL FOR CHAIR OR SIMILAR ARTICLE

Robert E. Kjer Jakobsen, Los Angeles, Calif., assignor to Schlumberger Limited (Schlumberger N.V.), Houston,
Tex., a corporation of Netherlands Antilles

Filed Nov. 15, 1965, Ser. No. 88,088

Term of patent 14 years

(Cl. D15—1)

FIG. 1 is an isometric view of a pedestal for chair or similar article in accordance with my design;

FIG. 2 is a front view thereof; and

FIG. 3 is a bottom view thereof.

I claim:

The ornamental design for a pedestal for chair or similar article, substantially as shown.
